CLAIM

The ornamental design for a cassette tape carousel, as shown and described.

DESCRIPTION

FIG. 1 is a perspective view of a cassette tape carousel showing my new design;

FIG. 2 is a side elevational view, the sides not shown being substantially identical thereto;

FIG. 3 is a top plan view thereof; and

FIG. 4 is a bottom plan view thereof.

The environmental structure shown in dotted lines in FIGS. 2 and 3 are for illustrative purposes only.

FIG. 1.

FIG. 4

FIG. 2.

FIG. 3.
